UNITED STATES PATENT OFFICE

2,424,605

FEATHERABLE PIN TYPE OARLOCK

William Harrison Edmonson, Jr.,
Bridgewater, Va.

Application January 7, 1946, Serial No. 639,518

6 Claims. (Cl. 9—26)

1 My instant invention relates to row boats and has for its object to provide a pin type oar lock which may be readily feathered.

Another object of this invention is to provide a pin type oar lock from which the oar is readily removable.

A further object of my invention is to provide an oar lock of pin type in which the oar has perfectly free movement in every necessary position.

A still further object of the invention is to provide in an oar lock a self securing and releasing spindle.

Other features and advantages will become more readily apparent from the following description and the accompanying illustrative drawings in which:

Figure 1 is a sectional elevation of my improved oar lock.

Figure 2 is a section on line 2—2 of Figure 1, and

Figure 3 is a sectional elevation illustrating a modification.

While one embodiment of the invention is illustrated in the above referred to drawings, it is to be understood that they are merely for the purpose of illustration and that various changes in construction may be resorted to in the course of manufacture in order that the invention may be utilized to the best advantage according to circumstances which may arise, without in any way departing from the spirit and intention of the device, which is to be limited only in accordance with the appended claims. And while there is stated the primary field of utility of the invention it remains obvious that it may be employed in any other capacity where it may be found applicable.

Referring to the drawings, 10 and 11, indicate two forms of my invention, the former consisting of a sectional ring 12, the lower portion 13, of which is fixed to a spindle 14. Hinged to the upper ends 15 and 16, of the section 13, as at 17 and 18, are segments 19 and 20, of the ring, the contacting ends 21 and 22, being enlarged as at 23 and 24, in each of which are bores 25 and 26, respectively, the former from the inner surface 27, of enlargement 23, and the latter being bored from the outer surface 28 of enlargement 24, said bores being horizontally disposed and neither extending entirely through, except insofar as a reduced slot 29, at the lower part of bore 26, through which slot the head end 30, of a spring catch 31, is adapted to project. The ring end 32 of the catch is secured to a pin 33, traversing the rear end of bore 25, and a spring 33' normally holds

2 the catch raised. The head 30, of the catch engages the rear upper wall surface 35 of bore 26, to hold the members 19 and 20, locked together. These members automatically lock due to the incline 36 of the said catch head. To unfasten the catch it is only necessary to project a finger into the bore 26, and push the head 34 down and pull members 24 and 25 apart.

10 The ring 12 is provided with an integral annular channel 31, within which is seated a ring 38, which is free to rotate in said channel 31. The ring 38, is also provided with a threaded aperture indicated at 39, within which the reversely threaded ends 40 and 41, of pins 42 and 43, are engageably received. These pins 42 and 43, have their other ends 42' and 43', screwed into the opposing enlargements 44 and 45, of a supporting ring 46, for the oar 47. The pins 42 and 43, due to their reverse threaded ends 40 and 41 engaging 15 the ring 38 and their opposite normally threaded ends 42' and 43' engaging the ring 46, act as pivot means between the ring 38 and the supporting ring 46.

25 The spindle 14, is provided with an annular flange 48, which is adapted to seat upon the upper end 49, of a socket member 50, secured in the rim of a boat gunwale. The lower end 51, of the spindle is bifurcated and within which are pivoted the upper ends of a pair of latches 52 and 53, having V-shaped lower catches 54 and 55, which are adapted to normally hold the spindle from jumping from its socket. Under pressure upon the lower inclines of the catches they will push in upon the spring 56, whereby the device will enter through said socket 50, and when the said catches pass the lower edge 57, of the socket they will spring out and engage said edge for said normal retention of the spindle. To remove the oar lock a sufficient pull thereupon will cause the upper inclines of the catches to again close the same in upon the tension of spring 56, and release the spindle.

35 In Figure 3 of the drawings, I show a modification in which a ball retaining ring 58, operates in the channel 59, of oar lock ring 60, the balls 61, seating through ring 60, project from both outer and inner surfaces of the ring to contact surfaces 62, of the channel 59, and also the outer surface 63, of the oar supporting ring 64, providing a double ball bearing action between the oar and its lock.

40 When the quarter sections 19 and 20, of the open ring 12, are opened up free passage is provided for the oar 47, and its ring 46, for removal 50 of the oar from the lock.

3

From the foregoing specification it will become apparent that the invention disclosed will adequately accomplish the functions for which it has been designed and in an economical manner and that its simplicity, accuracy and ease of operation are such as to provide a relatively inexpensive device considering what it will accomplish and that it will find an important place in the art to which it appertains when once placed on the market.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described the invention that which is claimed to be new and desired to be procured by Letters Patent is:

1. In a device as described an outer ring, an intermediate ring and an inner ring for supporting an oar, said intermediate ring rotatable upon the outer ring, said outer ring being formed in segments and provided with an inner channel in which the intermediate ring seats, means whereby the inner ring is supported by the intermediate ring, said means comprising a pair of pivot pins threaded into the inner and intermediate rings, said segments being hingedly connected, means for locking the same into a ring, a spindle supporting the outer ring, means carried by the spindle for securing the same in a socket, said last means including a release for the spindle.

2. In a device as described an outer ring, an intermediate ring and an inner ring for supporting an oar, said intermediate ring rotatable upon the outer ring, said outer ring being formed in segments and provided with an inner channel in which the intermediate ring seats, means whereby the inner ring is supported by the intermediate ring, said means comprising a pair of pivot pins threaded into the inner and intermediate rings, said segments being hingedly connected, means for locking the same into a ring, a spindle supporting the outer ring, and means carried by the spindle for securing the same in a socket.

3. In a device as described an outer ring, an intermediate ring and an inner ring for supporting an oar, said intermediate ring rotatable upon

the outer ring, said outer ring being formed in segments and provided with an inner channel in which the intermediate ring seats, means whereby the inner ring is supported by the intermediate ring, said means comprising a pair of pivot pins threaded into the inner and intermediate rings, said segments being hingedly connected, means for locking the same into a ring, and a spindle supporting the outer ring.

10 4. In a device as described an outer ring, an intermediate ring and an inner ring for supporting an oar, said intermediate ring rotatable upon the outer ring, said outer ring being formed in segments and provided with an inner channel in which the intermediate ring seats, means whereby the inner ring is supported by the intermediate ring, said means comprising a pair of pivot pins threaded into the inner and intermediate rings, said segments being hingedly connected, and means for locking the same into a ring.

20 5. In a device as described an outer ring, an intermediate ring and an inner ring for supporting an oar, said intermediate ring rotatable upon the outer ring, said outer ring being formed in segments and provided with an inner channel in which the intermediate ring seats, means whereby the inner ring is supported by the intermediate ring, said means comprising a pair of pivot pins threaded into the inner and intermediate rings, said segments being hingedly connected.

30 6. In a device as described an outer ring, an intermediate ring and an inner ring for supporting an oar, said intermediate ring rotatable upon the outer ring, said outer ring being formed in segments and provided with an inner channel in which the intermediate ring seats, means whereby the inner ring is supported by the intermediate ring, said means comprising a pair of pivot pins threaded into the inner and intermediate rings.
